UNITED STATES PATENT OFFICE

2,513,880

FOLDING STOOL

John Lang, Detroit, Mich.

Application July 27, 1948, Serial No. 40,810

4 Claims. (Cl. 155—149)

1
My invention relates to improvements in folding stools for camping, and like purposes.

The primary object of the invention is to provide a light weight, strong, folding stool of flat stock such as fiber board, wall board, or sheet plastic, and whereby the stool may be manufactured for sale at a very low cost.

Another object is to provide a stool constructed principally of such stock and which is foldable easily and quickly into a flat compact condition.

Other and subordinate objects, together with the precise nature of my improvements, will be readily understood when the succeeding description and claims are read with reference to the drawings, accompanying and forming part of this specification.

In said drawings:

Figure 1 is a view in perspective of my improved folding stool in a preferred embodiment thereof unfolded;

Figure 2 is a view in vertical transverse section partly broken away and drawn to a larger scale;

Figure 3 is a view in perspective illustrating the manner in which the stool is folded;

Figure 4 is a view in perspective illustrating the stool folded.

Referring to the drawings by numerals, my improved stool, as illustrated, comprises a plurality of rectangular seat supporting panels including a pair of opposite, intermediate, like panels 1, 2 inclining upwardly in relatively flaring relation with bottom edges 3 adapted to rest on the ground or floor, and hinged together, as at 4, for folding flat one against the other, and a pair of outer panels, 5, 6, like the panels 1, 2 inclining downwardly and outwardly of the intermediate panels 1, 2, respectively, in flaring relation thereto with upper edges 7, 8 hinged, as at 9, 10 to the upper edges 11, 12 of the intermediate panels 1, 2 for folding flat against the outer sides of said intermediate panels 1, 2.

A seat carrying strip 13 extends along the upper edges 7, 11 of said panels 1, 5 over the same and the hinge 9, and is hinged to the upper edge 11 of the intermediate panel 1, as at 14, to fold flat against the inner side of said panel 1.

A seat panel 15, like the other panels, extends from the seat carrying strip 13 over the upper edges 12, 8 of the panels 2, 6 and rests on said upper edges 12, 8 with a rear edge 16 hinged, as at 17, to one edge of said strip 13 for folding of the seat panel 15 over the folded panels 2, 6.

Bottom corner cleat blocks 18 at the front edge of the seat panel 15 hook over the upper edge 8 of the outer panel 6 and hold the intermediate

2
panels 1, 2 in up-swung, inclining, flaring relation by preventing the same from swinging away from each other on the hinge 4.

Flexible tie cords 19 connect the intermediate panel 1 to the outer panel 5, at the sides of said panels, and adjacent the bottom edges thereof, and hold said panels in downwardly inclining flaring relation against separative movement. Similar tie cords 20 similarly connect the intermediate panel and the outer panel 6 for the same purpose.

To fold the described stool, it is merely necessary to swing the top panel 15 upwardly on its hinge 17 to free the cleat blocks 18 from the upper edge of the outer panel 6, then, by pressure exerted against the outer panels 5, 6 swing said outer panels against the intermediate panels 1, 2, thereby swinging said panels 1, 2 into substantially flat engagement, after which the seat panel

20 15 may be swung on its hinge 17 over and against the folded panel 6, all as shown in Figure 4. The stool is thus collapsed into compact, flat condition for carrying or storing and with the tie cords 19, 20 in between the intermediate panels

25 1, 2 and the outer panels 5, 6.

As will be manifest, the panels 1, 2, 5, 6, 15, and the strip 13 may all be cut, or stamped out of flat stock such as fiber board, wall board, sheet plastic, or even sheet metal, and because such material is comparatively inexpensive, the stool may be manufactured at a very low cost while, at the same time, a stool is provided which is sturdy, adapted to last a long time, and easy to carry about, or transport.

35 The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

Having described the invention, what is claimed as new is:

45 1. A folding stool comprising a plurality of seat supporting rectangular sections of flat sheet material including a pair of opposite intermediate panels inclining upwardly in relatively flaring relation and having bottom ground engaging edges hinged together for folding of said panels into substantially flat engagement, a pair of outer panels like the intermediate panels inclining downwardly and outwardly from the intermediate panels and hinged to upper edges of the intermediate panels to fold toward the same,

a seat panel connected to the upper edge of an intermediate panel and having means thereon engaging the remote one of the outer panels to prevent said intermediate panels from swinging apart and means connecting the intermediate panels to the outer panels to prevent the same from swinging apart.

2. A folding stool comprising a plurality of seat supporting rectangular sections of flat sheet material including a pair of opposite intermediate panels inclining upwardly in relatively flaring relation and having bottom ground engaging edges hinged together for folding of said panels into substantially flat engagement, a pair of outer panels like the intermediate panels inclining downwardly and outwardly from the intermediate panels and hinged to upper edges of the intermediate panels to fold toward the same, a seat panel having a connection to the upper edge of an intermediate panel and having means thereon engaging the remote one of the outer panels to prevent said intermediate panels from swinging apart and means connecting the intermediate panels to the outer panels to prevent the same from swinging apart, said connection including a hinge providing for folding of the seat panel alongside one outer panel when the intermediate and outer panels are folded.

3. A folding stool comprising a plurality of seat supporting rectangular sections of flat sheet material including a pair of opposite intermediate panels inclining upwardly in relatively flaring relation and having bottom ground engaging edges hinged together for folding of said panels into substantially flat engagement, a pair of outer panels like the intermediate panels inclining downwardly and outwardly from the intermediate panels and hinged to upper edges of the intermediate panels to fold toward the same, a seat panel connected to the upper edge of an

intermediate panel and having means thereon engaging the remote one of the outer panels to prevent said intermediate panels from swinging apart, and means connecting the intermediate panels to the outer panels to prevent the same from swinging apart, the means last mentioned comprising flexible members.

4. A folding stool comprising a plurality of seat supporting rectangular sections of flat sheet material including a pair of opposite intermediate panels inclining upwardly in relatively flaring relation and having bottom ground engaging edges hinged together for folding of said panels into substantially flat engagement, a pair of outer panels like the intermediate panels inclining downwardly and outwardly from the intermediate panels and hinged to upper edges of the intermediate panels to fold toward the same, a seat panel connected to the upper edge of an intermediate panel and having means thereon engaging the remote one of the outer panels to prevent said intermediate panels from swinging apart, and means connecting the intermediate panels to the outer panels to prevent the same from swinging apart, the means first mentioned comprising corner blocks on the seat panel hooking over the upper edge of said one of the outer panels.

JOHN LANG.
